UNITED STATES PATENT OFFICE.

ALEXANDER BOYNTON, OF SAN ANTONIO, TEXAS.

SWAB.

Application filed November 10, 1923. Serial No. 674,024.

To all whom it may concern:

Be it known that I, ALEXANDER BOYNTON, a citizen of the United States, residing at San Antonio, in the county of Bexar, State of Texas, have invented certain new and useful Improvements in Swabs, of which the following is a specification.

This invention relates to swabs especially adapted for use in wells.

10 An important object of the invention is to provide a swab which upon being withdrawn from the well will create a vacuum in the lower portion of the well, whereby obstructions surrounding the perforated liner will be broken down and drawn into the well, where they can be removed by bailing to allow the oil, water, or gas to enter the well.

20 A further object of this invention is to provide a swab especially adapted for polishing and cleaning a casing and liner of a well for reducing and minimizing friction and thereby facilitating the movement of the products of the well to the surface.

25 A further object of the invention is to provide a well swab which may be used as a pump in an ordinary working barrel in an efficient and expeditious manner.

30 A further object is to provide a swab which may be conveniently converted into a bailer.

35 A further object is to provide a swab of highly simplified construction durable in use, and which may be operated without the exercise of a high degree of skill.

Other objects and advantages will be apparent during the course of the following description.

40 In the accompanying drawings forming a part of this application, and in which like numerals are employed to designate like parts throughout the same,

Figure 1 is a side elevation of the improved swab,

45 Figure 2 is a vertical sectional view through the same,

Figure 3 is a fragmentary perspective view of the improved swab,

50 Figure 4 is a sectional view of a slightly modified form of the invention,

Figure 5 is a horizontal sectional view taken on the line 5—5 of Figure 4.

Figure 6 is a horizontal sectional view taken on the line 6—6 of Figure 4,

55 Figure 7 is a horizontal sectional view taken on the line 7—7 of Figure 4,

Figure 8 is a group perspective view of a portion of the invention, and

Figure 9 is a detail view illustrating a slight modification of the invention. 60

In the drawing, the numeral 5 designates a tubular body upon which upper and lower rings or sealing members 6 are mounted. The rings 6 may be of rubber or other material capable of expanding into engagement with the liner or casing of a well so as to cut off the passage of fluid. Fig. 2 plainly illustrates the expansible sealing members or rings 6 which are securely held against endwise movement on the body 6 by inner and outer rings or nuts 7, and, of course, the holding member or nuts 7 properly space the expansible rings 6 on the tubular body. 65

In carrying out the invention a protector 8 is mounted upon the tubular body and extends over the expansible members 6 so as to prevent the expansible members from coming in destructive contact with the ends of the pipe sections, cracks, splits, seams, 70 burs, or other imperfections in the pipe. 75

The protector 8 consists of a plurality of lengths of wire secured in any suitable manner to end rings 9 which are in turn held upon the tubular body by end ring fastening collars 10. It is important to note that the rings 9 consist of semi-circular sections to which the ends of the wires are connected and, therefore, the protector may be quickly divided when it is desired to detach 80 the same from the swab. 85

More specifically, the protector consists of a pair of semi-circular sections which when assembled, as illustrated in Figure 1, will completely surround the expansible members 6 and effectively protect the same. The end rings 9 are formed with end flanges 11 adapted to be received in the rabbeted ends of the collars 10 so that the collars not only hold the end rings against endwise movement 100 but also hold the sections of the ring together. This feature of the invention is clearly illustrated in Figure 4. 95

The intermediate portions of the wires forming the protector are bowed inwardly into engagement with the body 5 and are held in position by means of an intermediate fastening ring 14. With reference to Figure 5 it will be observed that the intermediate fastening ring consists of a pair of 105 semi-circular sections secured to the body 5 by means of screw bolts 15 or other suitable

means. When it is desired to detach the protector 8 it is merely necessary to remove the screw bolts 15 and detach the sections forming the ring 14. The end ring fastening 5 collars 10 are merely backed or loosened sufficiently to free the flanges 11 and the sections of the protector may be detached from the body. It will be seen that the ends of the collars 10 not only hold the rings 9 in 10 place, but also positively prevent objects from entering the ring and the body.

Figure 2 illustrates that a dart 16 is secured to the lower collar 10 by means of a valve seat 18 and contrary to usual practice the valve guard is held off its seat by means of a coil spring 20. The upper end of the dart is provided with an extension 21 having its upper end formed with a head with which one end of the coil spring 20 is 20 engaged and the other end of the spring is engaged with the top of valve seat 18.

In operation, the swab is lowered in the well and when raised the fluid pressure entering through the perforated nipple 20 is 25 transmitted to the inside of the expandable members 6 through the medium of apertures 22 in the body 5. This causes the rubber rings to expand against the casing or liner so that if the swab is raised all fluid above 30 the rubber rings is raised out of the well.

Two rubber rings are used because joints in the casing and imperfections in the pipe might not be completely sealed off by a single rubber ring. By using two rings one 35 will hold while the other is passing a joint or imperfection in the casing.

The spring 20 is of such tension that it normally holds the dart in its elevated or unseated position. When the swab is lowered too far into the fluid so that the load 40 cannot be lifted by the bailing line, the swab is merely lowered back into the fluid so that the pressure from below equalizes the pressure from above the dart. At this 45 point the dart will rise, whereupon the swab may be slowly withdrawn by applying just enough power to move the same upward without causing the dart to seat. When the swab has been raised to a point where 50 the operator estimates the load can be lifted, he applies more power, thus increasing the upward speed of the swab which immediately seats the dart valve. If the load is still too great, the swab is lowered as before and 55 again slowly withdrawn as before, but to a still higher level. This process is repeated until a proper load is found to be above the swab, whereupon the same is withdrawn from the well.

60 Special attention is directed to Figure 8 which illustrates that the rings 6 are provided with longitudinal grooves 28 to receive the marginal portions of the wires forming the protector. Approximately two-thirds of the adjacent portions of the wires 65

are received in the grooves 28 and as a result of continued use of the dart the exposed portions of the wire will wear so that a perfectly smooth surface is provided.

In use the wires of the protector will wear about as fast as the rubber rings 6 and a liquid tight connection between the casing or liner and the rubber rings will be provided.

One, two, three or more joints of pipe are 75 threaded onto the swab to give the swab sufficient weight to unspool the bailing line from the draw works and cause the swab to descend rapidly, notwithstanding the friction of the rings against the casing or liner. 80

The improved swab will pick up the fluid above the rubber rings and as the swab is being withdrawn a suction or vacuum is created below the same. This suction or vacuum thus created enables gas, oil, or water to break through any obstructions surrounding the liner and thereby enter the liner. This swab polishes and cleans the casing and liner of the well for reducing friction and thereby facilitating the discharge of the 85 liquid or gas.

Also the swab may be used as a plunger pump in an ordinary working barrel. As a pump it is highly efficient until the rubber rings completely wear out; whereas, the ordinary cups begin to lose their efficiency from the period of first use.

Also the swab may be converted into a washing tool by omitting the perforated nipple 20 and substituting a perforated body 95 for the main body 5.

To remove water or slush from beneath the oil in a well two or more joints are 100 screwed onto the pipe above the swab to provide the necessary weight and a bailing line is fastened to the top of the same with an ordinary open bailer top. This form of the invention is illustrated in Figure 4 wherein it shows that the dart in this case is not employed. By letting the swab or bailer as 105 now constructed down below the oil and into the water or slush and withdrawing the same from the well the water or slush is brought out of the well and the oil is allowed to escape down through the open pipe or bailer.

110 In the form of the invention illustrated in Figure 9, the lock nuts 50 are provided with inwardly directed annular flanges 51 received in annular grooves received in opposite edges of packing rings 52, whereby to provide an efficient seal between the lock nuts and the rings. Therefore, when the fluid under pressure passes through the apertures and engages the inner sides of the packing rings, the packing rings will be forced against the liner or casing and an absolutely liquid tight connection will be provided. Of course, the flanges being received 115 in the grooves in the rings prevent leakage 120 125 130

and, therefore, enables the invention to operate with a high degree of efficiency.

I claim:

1. A tool of the character specified comprising a body having discharge means, an expansible packing member mounted on said body and surrounding said discharge means, and a protector surrounding said expansible packing member and consisting of a plurality of separate sections.
2. A tool of the character specified comprising a body having discharge means located at spaced points, expansible sealing means mounted on said body and surrounding said discharge means, said expansible sealing members being adapted to contact with the interior wall of a liner or casing, and a protector surrounding said expansible sealing members and consisting of a pair of separate sections.
3. A tool of the character specified comprising a body having discharge means located at spaced points, expansible sealing means mounted on said body and surrounding said discharge means, said expansible sealing members being adapted to contact with the interior wall of a liner or casing, a protector surrounding said expansible sealing members and consisting of a pair of separate sections, and means encircling the intermediate portion of said protector for connecting the intermediate portion of the protector to the body and for holding the sections of the protector together.
4. A tool of the character specified comprising a body having discharge means, expansible casing and liner contact members mounted on said body outwardly of said discharge means, a protector surrounding said sealing members and consisting of a plurality of separate sections, and a fastening ring surrounding the intermediate portion of the protector for connecting the sections of the protector to the body.
5. A tool of the character specified comprising a body having discharge means, expansible casing and liner contact members mounted on said body outwardly of said discharge means, a protector surrounding said sealing members and consisting of a plurality of separate sections, and a fastening ring surrounding the intermediate portion of the protector for connecting the sections of the protector to the body, said fastening ring consisting of a plurality of arcuate sections.
6. A tool of the character specified comprising a body having discharge means, expansible casing and liner contact members mounted on said body outwardly of said discharge means, a protector surrounding said sealing members and consisting of a plurality of separate sections, and a fasten-

ing ring surrounding the intermediate portion of the protector for connecting the sections of the protector to the body, said fastening ring consisting of a plurality of arcuate sections, and means connected to said body and receiving the end portions of said protector whereby to hold the sections of the protector together.

7. A tool of the character specified comprising a body, casing and liner contact members mounted at spaced points on said body, a protector surrounding said casing and liner contact members and consisting of a plurality of separate sections, and means mounted on said body and having interfitting connection with the ends of said protector to hold the sections of the protector together and in position.

8. A tool of the character specified comprising a body, casing and liner contact members mounted at spaced points on said body, a protector surrounding said casing and liner contact members and consisting of a plurality of separate sections, means mounted on said body and having interfitting connection with the ends of said protector to hold the sections of the protector together and in position, and means securely connecting the intermediate portion of the protector to the body.

9. A tool comprising a body having discharge apertures, expansible sealing members surrounding said apertures, locking rings mounted on said body and engaging opposite ends of said sealing members, there being an interfitting connection between said locking rings and said expansible sealing members, and a protector securely connected at its intermediate portion to the body and extending over said expansible sealing members.

10. A tool of the character described comprising a body, a casing and liner contact members mounted at spaced points on said body, a protector surrounding said casing and liner contact members and consisting of separate sections, each section consisting of lengths of wire, arcuate attaching members connected to the ends of said wires and provided with a flange, and collars mounted on said body and receiving said flanges.

11. A tool comprising a pair of spaced casing and liner contact members having longitudinal grooves, a protector consisting of a plurality of lengths of wire, partially received in said grooves, the ends of said protector being provided with sectional rings having flanges, and collars receiving said flanges whereby to connect the sections of said rings and to hold the protector in position.

ALEXANDER BOYNTON.
